POWER UNIT

Fred P. Gerhardt, Nierstein, (Rhine), Germany

Application December 28, 1956, Serial No. 631,238

15 Claims. (Cl. 123—191)

This invention relates to new and useful improvements in power units or prime movers and in general is an improvement on the power unit covered by my prior United States Patent No. 2,534,590, dated December 19, 1950.

The general objects of the invention are to provide a power unit of the enclosed type wherein all the necessary events for a full and complete operation are carried out within a cylinder; and to provide a power unit driven by internal combustion which has a greatly increased efficiency and power without increasing the maximum pressures and temperatures normally found within a single cylinder unit with comparative compression ratios.

As such, the invention facilitates conversion into power a large proportion of the heat ordinarily lost in the cooling system and exhaust of conventional power units. The unit in accordance with the invention is equally well adapted for burning of fuel by spark ignition (constant volume) or by compression ignition (constant pressure).

The general operation and design of the invention is based on three major and well known premises: the theorem of Johann Bernoulli (1728); the experimental findings and calculations by Prof. George Wilson of Cambridge (1875); and since then the development of the de Laval nozzle. To the latter may be added the action within a diffusor which is largely like that of a nozzle in reverse. These basic factors are all well known, have been thoroughly proven, and are in general use daily. They have been particularly tested and formulated by Prof. Aurel Stodola.

The two basic laws of thermodynamics have been followed throughout, as expounded by well known authorities such as Carnot, Clausius, Thompson, Joule, Stodola, and others. These basic laws have been found to be true and universal and unchanged even by Einstein's findings and the theory of relativity.

Prof. George Wilson found by experiment and calculation that: If steam be allowed to expand behind a piston in a cylinder from P_1 to 0.57 P_1 adiabatically, the mean effective pressure will be about 0.33 P_1 . If a stream capable of exerting this mean pressure were allowed to flow through an orifice, it would be able, according to the principles governing the impulse of jets of fluid, to exert an impulsive pressure and, therefore, a reaction of twice the pressure corresponding to its static head, or 0.66 P_1 . Besides this pressure the reaction would be increased by the addition of the pressure in the orifice, or 0.57 P_1 absolute, the atmospheric pressure must be subtracted. The expression for the reaction then becomes:

$$=1.23 P_1 - 14.7 \text{ lbs. per sq. in. of orifice}$$

$$=1.23 P_1 - 14.7 \text{ lbs. per sq. in. of orifice}$$

The gases of combustion, mostly air, follow the same thermodynamic laws as steam when expanding or contracting, but P_1 becomes 0.527 P_1 for air, in the results given above.

These findings were and still are very important facts which form the basis of designs by Parsons and other turbine builders. However, steam and gases of com-

2

bustion are two very different power vehicles which have different characteristics even though they follow the same thermodynamic laws generally. These differences in characteristics demand different handling with different designs and construction of the necessary means to produce equal and comparatively useful results. This has been borne out by developments in the gas turbine field as compared to the steam turbine field, as known today. The gas turbine strictly as a turbine similar to the steam turbine has lagged far behind the steam turbine because the different characteristics and differences in handling gases of combustion instead of steam have not been used properly. The great temperature differences alone are primary factors which undeniably call for primary differences in means if the same or equal results are to be expected.

If a metal were found which could withstand the high temperatures involved, or a fuel with the necessary characteristics to enable a given combustible gas to replace steam within a standard turbine and perform equally well therein, a large air compressor and a large furnace as well as many additional stages of expansion would be required. The resultant power plant for equal power would be practically as large and cumbersome and difficult to maneuver as the present steam turbine plant and the overall efficiency would not be much greater, if at all.

In the present invention, all the factors and means included according to the laws of thermodynamics and mechanics indicate that the results obtained by Prof. George Wilson are attainable with gases within a piston and cylinder engine in a simple, practical and useful manner. Moreover, the power unit can be safely used in sizes large enough to compete with the largest steam turbine plants, very successfully as to both power and efficiency, but be very superior in maneuverability and adaptation to many uses for which the turbine, strictly as such, cannot be used.

The present invention will be understood by reference to the accompanying drawings, wherein like characters of reference are used to designate like parts, and wherein:

Figure 1 is a vertical sectional view of a power unit in accordance with the invention;

Figure 2 is a fragmentary sectional view, taken substantially in the plane of the line 2—2 in Figure 1;

Figure 3 is a cross-sectional view, taken substantially in the plane of the line 3—3 in Figure 2;

Figure 4 is a fragmentary sectional detail of one of the passages;

Figure 5 is a fragmentary vertical sectional view illustrating a modified form of the invention;

Figure 6 is a vertical sectional view of another modified form; and

Figures 7, 8 and 9 are graphical illustrations of some of the factors pertaining to the operation of the invention.

With particular reference to Figures 1—4 inclusive, the numeral 10 designates a cylinder of the power unit, the same being provided with an external head 11 which is secured thereto by suitable bolts 12. Disposed within the cylinder 10 and secured to the external head 11 by suitable bolts 13 is an internal head 14 which coacts in a manner hereinafter described with a reciprocable piston 15, equipped with the usual wrist pin 16 and connecting rod 17. The piston is also provided with the usual set of rings 18, while the external head 11 is provided with igniting means such as a spark plug 19. Suitably actuated inlet and outlet valves may be also provided in the head 11, as indicated at 20, 21, respectively.

The internal head 14 is recessed to provide a central combustion chamber 22 substantially of the configuration shown, and is also provided with an annular recess 23, coaxial with the chamber 22. The formation of the

chamber and recess 23 results in the provision of a set of annular, coaxial projections 14a, 14b on the head 14, which projections are receivable in complementary recesses 24, 25, respectively, formed in the piston 15. The formation of the recesses 24, 25 in the piston, in turn, results in the provision of an annular projection 15a on the piston, which is receivable in the complementary recess 23 of the head 14.

The projections 14a, 14b and 15a fit into the respective recesses 24, 25 and 23 with sufficient clearance to form a tortuous passage 26 which extends from the lower end of the chamber 22 between the interfitting projections of the piston and head 14 to the side wall of the cylinder 10 and extends therealong to the external head 11, at which point the passage 26 communicates with the upper end of the chamber 22 through a space 26a existing between the heads 11, 14. The drawings, of course, illustrate the piston at the top of its stroke, in which position the parts are interfitting as shown. As the piston travels downwardly, the projections 14a, 14b, 15a become withdrawn from the respective recesses 24, 25, 23, so that the volume of the passage 26 is substantially enlarged, although the volume of the chamber 22 remains the same.

The invention may be embodied in a four-cycle or a two-cycle engine, and the engine may be supercharged, if desired, in a conventional manner.

The engine in accordance with the invention is far more efficient than conventional engines as indicated by Prof. Wilson's experiments, and the power difference is still greater because of the greatly increased M. E. P. These differences are particularly achieved because of the method of "energy flow" utilized, and the structure represents simple and practical means of converting the energy flow into impulsive pressure and reaction, and therefore work on a moving piston exactly along the lines propounded by Prof. Stodola in his mathematical analysis and proof as developed in his theorem of Bernoulli. Therein he proves that within a given time in a given energy flow a reduction of energy between two cross-sections is reflected equally in the two cross-sections. In order to keep this flow continuous and in the same direction until the energy is used up, there must be a minimum (only one) cross-section with an expanding nozzle, and behind this a larger cross-section which forms the throat of a compression nozzle or diffusor which keeps on supplying the remaining or major part of the energy upon its return from the piston and lower head (internal head 14).

The minimum expansion nozzle is disposed in the chamber 22 at 27 and the small end of the diffusor is shown at 28. The space or portion of the chamber 22 between the regions 27, 28 is the combustion and compression chamber proper. The highest relative pressure of the system is always within the chamber 22 during the expansion stroke and therefore, the energy flow is continuous until it is all used up. Thermodynamically, the isothermal system finds existence in the chamber 22 as its only place; as the gas flows through the nozzle 27 its state changes from the isothermal to the adiabatic system, expanding through the nozzle and the "work well" between the piston 15 and the internal head 14 where the pressure is at its lowest. From that point of lowest pressure the design becomes a diffusor and the remaining or major part of the momentum of the gasses is gradually destroyed as it is changed to pressure and reaches its maximum relative pressure again within the chamber 22 after flowing through the section 28. The expansion side forms an adiabatic, the diffusor or compression side the other adiabatic, while the "work well" is located between the two. There is, therefore, only one isothermal and that is located in the chamber 22.

It is evident from the foregoing that this is an enclosed system from the beginning of the working stroke when the flow of energy is started by ignition and as long as

the flow of energy continues, to the end of the stroke when the gasses are exhausted in the usual manner. Each element of the gas at it returns to the chamber 22 is, of course, at a lower pressure after each trip through the work well, since there, a portion of its energy is given up as work against the piston. The piston is moving and the work well is increasing continually in volume, but the chamber 22 and most of the compression space is not. The size of the nozzle 27 is such that the pressure in the chamber 22 is always considerably greater than that in the nozzle 27. When velocity of gases above that of local speed of sound is required, then the ratio of pressures between the chamber 22 and the nozzle 27 must be as 1 is to 0.527. Since this is the highest ratio found in any cross-section of the system, the energy and the gas flow will be continuously in the same direction and continuously go through the events as above described until all or nearly all of the available energy is converted into work.

As will be apparent, friction and resultant heat of friction will exist, but in this design practically all the heat of friction is converted into work because each element of gas upon its return to the chamber 22 returns each time, or is transformed each time it returns back into the isothermal system which means that all the heat content of each element joins up each time with all the rest of the heat in the chamber 22 and helps build up and maintain the maximum relative pressure desired. It also forms part of the continuous energy flow which then flows through the nozzle 27 as the isothermal system changes to the adiabatic in or near the throat of the nozzle 27.

This design is therefore practical and workable in construction which is in a large measure similar to the improved theorem of Bernoulli. There is however one additional or practical feature, which is the work well. This and other practical differences exclude any attempt at perpetual motion. At this point a quotation from Osborne's Marine Engineers Manual may well be taken, which not only explains the theory of thermodynamics, but also practical working out and use thereof in engines. "Because of the many different conditions under which steam (and gas) may be caused to expand in performing actual work, the factors of expansion are variable quantities. These are known as adiabatic and isothermal expansion and are of great importance in the theory of performance of heat engines."

Adiabatic expansion.—"A gas is said to expand or be compressed adiabatically when it does not receive or give out heat, except in the form of external work. That is, there is no radiation or conduction of heat to or from the gas, as it is expanded or compressed in doing actual work. In other words, any external work done by the gas is done at the expense of the contained or internal energy of the gas. All the heat and internal energy lost during expansion of the gas goes to doing work. If compressed adiabatically, all the work done on the gas goes to increase its internal energy. Since any change in the internal energy of a gas depends upon a change in temperature, it is impossible to have an increase in the internal energy without an increase in temperature, or a decrease in internal energy without a decrease in temperature. In actual heat engines or compressors this is never true, and the adiabatic expansion or compression is only approximate. This theory of adiabatic expansion, however, serves in engineering calculations as an ideal or standard for comparing the actual performances of heat engines."

Isothermal expansion.—The term "isothermal" means equal heat. Isothermal expansion then means expansion at equal or constant temperature. A gas expands or contracts isothermally when its temperature remains constant during a change of volume. That is, in isothermal expansion or compression, a gas may be expanded from a higher to a lower pressure, or it may be compressed from a larger to a smaller volume; but in doing either it must absorb or give off enough heat to keep its temperature constant."

Practical examples of adiabatic and isothermal curves.—The foregoing may be better explained as follows: When a gas expands in a cylinder under a movable piston and the piston is moved by some force applied externally, then the volume and the pressure of the enclosed gas would change but the temperature would remain constant providing there were no losses due to radiation, etc. Therefore, the curve indicating the varying condition of the gas as to pressure and volume would be an isothermal curve. If however, the piston were moved by expenditure of the heat energy stored in the gas, then external work would be done by the gas and heat energy expended. The pressure would fall to below that of the isothermal curve. Then, if no other heat influences had been introduced, such as heat by conduction through the cylinder wall or gain of heat from some external source, the curve described would be an adiabatic curve."

The improvements possible with this method and design can also be proved mathematically and graphically, these proofs coinciding closely with the results found and demonstrated by Prof. Wilson, Mr. Rosenhain, and others. Such further proofs are as follows: The process herein described and of which this invention is a particular example of construction has been calculated by Prof. Stodola, Poincare and other authorities on thermodynamics. Stodola used a theoretical construction in his calculations to prove that the second law of thermodynamics was sound and unassailable even by the theory of relativity. (It can be found in Stodola's treatise on "Steam and Gas Turbines," 6th edition, 1924. For example, Stodola found and developed formulae for isothermal and adiabatic flow of steam or gases which are true and now in practical use. Figure 7 of the accompanying drawings shows a translation of the manner in which an energy flow of steam or gas goes through a series of narrowed down cross-sections. It is important to observe that the critical pressure P_m does not occur in every small cross-section, but only in the smallest or narrowest cross-section such as f_m (corresponding to the nozzle 27) since there in the relation $G=fq(p)$ the factor $q(p)$ must have the greatest possible value. G is the weight of flow, q is the velocity factor and p is the pressure. In the two narrowed down sections f'_m-f_m , the function $q(p)$ starting from A and moving toward f'_m will increase, but not to its highest value, the other side of f'_m the value $q(p)$ goes through also p with the same values as before, but p is reversed in direction. In B where f is a maximum, function $q(p)$ will be the smallest (without being analytically a minimum), the pressure has a maximum value. From B toward f_m the pressure reduces, and when $f'_x=f_x$, we also have the same p_x as before. Beyond f_m however, an expansion follows and when $f''_x=f_x$ again, then $q(p''_x)=q(p_x)_1$. On the other hand the pressure itself corresponds to a value less than p_x at a point the other side of the maximum of $q(p)$. Were $f'_m=f_m$, the pressures at both places would be the same.

The formula $G_{sec}=f_m q(p_m)$ represents the highest value of G_{sec} which can flow through a given cross-section under a given set of pressure conditions. A weight of flow where $G'_{sec} < G_{sec}$ is very possible. In this case the pressure becomes less toward f_m , $q(p)$ increases but without reaching the highest value at f_m . After this the same values of $q(p)$ and of p which took place before f_m must run through, that is, the steam or gas on the after or other side of the narrowest cross-section will again become compressed, and will theoretically with sufficient widening of the nozzle reach the same value that it had in the beginning or original chamber.

Consequently, such a flow when once set in motion, aside from the losses due to friction, etc., would continuously go around such a circuit. However, power losses take place therein as in any other engine and it would soon stop unless additional energy were not continually supplied to keep it moving.

In the invention hot gases may be made to convert heat energy into work by impulse and reaction against a piston, reaction taking place along with impulse when the velocity of flow is greater than the local speed of sound.

With reference again to Figures 1-4 of the drawings, it will be noted that although the nozzle 27 is disposed at the outlet of the chamber 22, the walls of the entire passage 26 form a continuous expanding nozzle in general which is a continuation of the nozzle 27 and operates in substantially the same manner until the gases reach the head space 26a. This is made possible by the fact that the flow of gases in general is radially outwardly from the center of the cylinder as well as axially along the direction of stroke. When the gases reach the outer wall of the cylinder 11 and the head space 26a they flow radially inwardly to the diffusor section 28. The remaining kinetic energy at the circumference of the space 26a along with the inner energy or heat and also the major part of the heat of friction caused by the flow, combine and unite in continuing the flow of gases into the chamber 22. Here the gas medium with its various energy components changes back into the isothermal system or state. During this action the pressure in the chamber 22 goes down continually because of the work done on the piston and because of some conduction and radiation losses. This reduction in pressure within the chamber 22 therefore follows the isothermal expansion curve very closely, but of course does not completely equal it.

The relative sizes of the nozzle 27, section 28, etc. are such that from the beginning to the end of the stroke the velocity and weight of gases flowing continuously will provide the right amount of impulse and reaction for a given engine.

It will be also observed that the aforementioned projections 14a, 14b and 15a have rounded extremities 29 and that the recesses 24, 25 and 23 have rounded bottom edges 30, the curvatures of the respective extremities 29 and edges 30 being of such diameters and spaced in such manner as to produce restricted regions 31 as is best shown in Figure 4. In these restricted regions of the passage 26 the gas will be somewhat compressed so that its speed is that of sound. The friction loss at such speed is low, since it is turned to heat which further assists expansion and is practically all converted to work.

There are great many phenomena in nature whose rate of increase is proportional to itself and the only known function which shows the variations is the exponential function where $y=e^x$, wherein the differential coefficient of e^x is e^x itself. The isothermal state and its change in a nozzle throat to an adiabatic state presents an energy content whose possibility to do work is shown by the well known formula

$$W = e^{-\frac{Q}{JKT}}$$

Entropy diagrams can also be constructed and the various heat and work contents compared to obtain a correct nozzle size. These, however, are cumbersome and hard to grasp. This particular invention however, lends itself to a simple graphical analysis and also gives a more complete picture which can serve well in calculating the various sizes of nozzles, etc. for engines of this type. In this analysis a simple gas engine indicator diagram is used as follows:

It can be proved that when a perfect gas (whose law is $pv=Rt$ for a pound of gas, R being constant and equal to $K-k$ the difference of the important specific heats; & is used to denote K/k) changes in its volume and pressure in any way, the rate of reception of heat (or release of heat) by it per unit change of volume, which may be called h (in work units) or

$$\frac{dH}{dv}$$

is

$$h = \frac{1}{\&-1} \frac{d}{dv} (pv) + p \quad (1)$$

or

$$h = \frac{1}{\&-1} \left(v \frac{dp}{dv} + \&p \right) \quad (2)$$

The factor

$$\frac{dp}{dv}$$

is very different from

$$\left(\frac{dp}{dv} \right)$$

because it may be given any suitable value. Heat is assumed to be expressed in work units so as to avoid the unnecessary introduction of J for Joule's equivalent. When gas expands according to the law

$$pv^s = c \quad (3)$$

a constant,

$$h = \frac{\&-s}{\&-1} p \quad (4)$$

Evidently, when $s = \&$, $h = 0$, and therefore we have $pv\& = \text{constant}$ as the adiabatic law of expansion of a perfect gas. $\&$ is 1.41 for air and 1.31 for the particular gas in the engine cylinder. When $s = 1$, so that the law of expansion is pv constant, we have the isothermal expansion of a gas and we notice that here $h = p$, or the rate of reception (or giving up) of heat energy is equal to the rate of the doing of mechanical energy. It can be seen that in any case where the law of change is given by Formula 3, h is exactly proportional to p . If s is greater than $\&$, the gas is having heat withdrawn from it. If the Equation 1 be integrated with regard to v , we have

$$H = \frac{1}{\&-1} (p_1 v_1 - p_0 v_0) + W \quad (5)$$

Here H is the heat given to a pound of perfect gas between the states p_0, v_0, t_0 and p_1, v_1, t_1 and W is the work done by it in expanding from the first to the second state. This expression may be put in other forms because we have the connection

$$pv = Rt \quad (6)$$

Thus, if the volume keeps constant, $W = 0$ and the change of pressure due to ignition and the gift of a known amount of heat may be found. If the pressure keeps constant, W is $p(v_1 - v_0)$ and the change of volume due to the reception of heat is easily found. Another useful expression is

$$\frac{dH}{dv} = k \frac{dt}{dv} + p \quad (7)$$

where k is a constant, being the specific heat at constant volume. Integrating this with regard to v , we find

$$H = k(t_1 - t_0) + W \quad (8)$$

This gives us exactly the same answer as the last method and may at once be derived from (5) and (6). In this form one sees that if no work is done, the heat given is $k(t_1 - t_0)$ and also that if there is no change of temperature, the heat given is equal to the work done. In applying the above, two diagrams were made for h , one for the adiabatic expansion and one for the isothermal (the isothermal expansion curve here is h itself), using $s = 1.31$, a stroke of 3.37 inches and a compression ratio of 7 to 1, as shown in Figure 9. h is the rate at which the gas shows that it is receiving heat in foot-pounds per unit change of volume, on the assumption that is a perfect gas receiving heat from some furnace. (In fact, it

is its own furnace, the heat coming from its own chemical energy.) Just as pressure is

$$\frac{dw}{dv}$$

the rate at which work is done per unit change of volume, so is

$$h = \frac{dH}{dv}$$

It is to be observed that h is in the same units as p , and to draw a curve for h it is not necessary to pay any attention to the scales for either p or v . They may be measured as inches on the diagram. Using these values and having found h or

$$\frac{dH}{dt}$$

at every place, and it is desired to find the rate per second at which the gas is receiving (or giving off) heat, if t represents time,

$$\frac{dH}{dt} = \frac{dH}{dv} \times \frac{dv}{dt}$$

and so it is only necessary to multiply h by

$$\frac{dv}{dt}$$

As

$$\frac{dv}{dt}$$

is represented by the velocity of the piston and as the motion of the piston is, as a first approximation simple harmonic a semicircle is described upon the distance on the diagram which represents the stroke and the ordinates of the semicircle represent

$$\frac{dv}{dt}$$

We therefore multiply every value of h by the corresponding ordinate of the semicircle and obtain, to a scale easily determined, the diagram which shows at every instant

$$\frac{dH}{dt}$$

This is shown in Figure 9, the curve

$$\frac{dH^a}{dt}$$

being for adiabatic and the curve

$$\frac{dH^{is}}{dt}$$

for isothermal.

As will be observed, the slope of each is practically equal to its ordinate as in exponential curves in general. The area under each shows the energy available in foot-pounds and their comparative ratio. This ratio is also shown by the slope of these curves. The curves clearly show that although the maximum pressures are the same, the work available and therefore the mean effective pressure is much greater with the present invention. They also show that the pressure on the piston reduces in a straight line ratio which means that in a piston and cylinder engine, a given sized nozzle may be calculated from the usual formulae used to fit the requirements of a given engine in order to use up most of the available energy during the length of the stroke. There is a steady and even reduction of pressure from the beginning to the end of the stroke.

In the diagram shown in Figure 8, the curve A, according to Mr. Rosenhain's experiments, indicates velocity corresponding to measured reaction of the jet from an expanding nozzle, while curve B represents calculated

velocity, assuming that all the heat energy concerned in the drop from the higher pressures before the nozzle to the constant atmospheric pressure beyond was converted into kinetic energy of the jet stream. Y is percentage loss in efficiency.

Referring now to the accompanying Figure 5 which shows a modified arrangement of the invention wherein the external head 11 is provided with a depression 31 having the igniting means 19 mounted therein, the depression 31 coating with the internal head 14 to provide the diffuser region 28a adjacent the center of the space 26a in place of the region 28 of Figure 1. The total cross-section of the region 28a is greater than the cross-section of the nozzle 27 and, as in Figure 1, the cross-sections in the passage 26 are greater than the nozzle, so that the nozzle is the only minimum cross-section in the gas flow.

Figure 6 illustrates another modified embodiment of the invention wherein the cylinder 32 is provided with an external head 33 which is secured thereto by suitable screws 34, while an internal head 35 is secured to the head 33 by suitable screws or bolts 36. The igniting means are shown at 37, while 38 is the piston reciprocable in the cylinder. The piston is provided with a wrist pin 39 and with a set of rings 40.

In this form of the invention the aforementioned tortuous passage 26, 26a of Figures 1 and 5 is substituted by a comparatively simple passage 41 which extends from the nozzle 42 of the combustion chamber 43 in the head 35 downwardly, radially outwardly and then upwardly between curved projecting bottom portions 35a of the internal head 35 and complementally curved recesses 38a formed in the piston 38, as will be clearly apparent. The passage 41 then continues upwardly and radially inwardly through a space 44 between the heads 33, 35 to a diffuser region 45 at the top of the chamber 43. As will be apparent, this form of the invention is considerably simpler than the forms of Figures 1 and 5, but the operating characteristics thereof are substantially the same.

While in the foregoing there have been described and shown the preferred embodiments of the invention, various modifications may become apparent to those skilled in the art to which the invention relates. Accordingly, it is not desired to limit the invention to this disclosure, and various modifications may be resorted to, such as may lie within the spirit and scope of the appended claims.

What is claimed as new is:

1. In a gas expansion engine, the combination of a cylinder, a head thereon provided with a combustion chamber, a piston reciprocable in said cylinder and spaced from said head at the top of its stroke to provide an expansible gas passage therebetween in communication with said chamber, and means for returning gases from said passage through said head to said chamber.

2. The engine as defined in claim 1 wherein said chamber is of a fixed volume.

3. The engine as defined in claim 1 together with a restricted nozzle provided in said head between said chamber and said passage.

4. In a gas expansion engine, the combination of a cylinder, a head thereon, and a piston reciprocable in said cylinder, said head being provided with a combustion chamber and with a gas return passage communicating with said chamber, said piston at the top of its stroke being spaced from said head to provide an expansible gas passage communicating with said chamber and with said return passage, whereby gases expanding in said expansion passage may be returned to said chamber.

5. The engine as defined in claim 4 wherein said head is provided with a restricted nozzle between said chamber and said expansible passage.

6. The engine as defined in claim 4 wherein said head is provided with a gas diffusor section between said return passage and said chamber.

7. The engine as defined in claim 4 wherein said chamber is of a fixed volume.

8. In a gas expansion engine, the combination of a cylinder, an external head provided thereon, an internal head secured to said external head in said cylinder and provided with an axially elongated combustion chamber of a fixed volume having a restricted nozzle at its lower end, said internal head being spaced from said external head to provide a return gas passage therebetween in communication with the top of said chamber, and a piston reciprocable in said cylinder and spaced at the top of its stroke from said internal head to provide an expansible gas passage communicating with said return passage and with said nozzle, whereby gases expanding in said expansible passage may be returned to said chamber.

9. The engine as defined in claim 8 wherein the spacing between the external and internal heads provides a gas diffusor section between said return passage and said chamber.

10. The engine as defined in claim 8 together with at least one annular projection provided on said internal head and having an annular recess adjacent thereto, said piston having an annular recess receiving said projection, and an annular projection provided on said piston adjacent the recess therein and received in the recess in said internal head, said projections on said internal head and piston being spaced apart to constitute said expansible gas passage.

11. The engine as defined in claim 10 wherein said projections have rounded extremities and wherein the recesses in said internal head and piston are complementally rounded.

12. In a gas expansion engine, the combination of a cylinder, an external head provided thereon, an internal head secured to said external head in said cylinder and provided with an axially elongated combustion chamber of a fixed volume having a restricted nozzle at its lower end, said internal head being spaced from said external head to provide a return gas passage therebetween in communication with the top of said chamber, a piston reciprocable in said cylinder, a set of circumferentially spaced annular projections provided on said internal head, and an annular projection provided on said piston and received in the space between the projections of said internal head, said piston being spaced at the top of its stroke from the internal head to provide a tortuous expansible gas passage between said projections, said expansible passage communicating with said return passage and with said nozzle, whereby gases expanding in said expansible passage may be returned to said chamber.

13. The engine as defined in claim 12 wherein said nozzle affords the smallest cross-section of gas flow in the engine.

14. In a gas expansion engine, the combination of a cylinder, an external head provided thereon, an internal head secured to said external head in said cylinder and provided with an axially elongated combustion chamber of a fixed volume having a restricted nozzle at its lower end, said internal head being spaced from said external head to provide a return gas passage therebetween in communication with the top of said chamber, a piston reciprocable in said cylinder, and an annular projection provided on said internal head, said piston being provided with an annular recess receiving said projection, the piston being spaced at the top of its stroke from said internal head to provide an expansible gas passage at said projection in said recess, said expansible passage communicating with said return passage and with said nozzle, whereby gases expanding in said expansible passage may be returned to said chamber.

15. The engine as defined in claim 14 wherein said nozzle affords the smallest cross-section of gas flow in the engine.
